Fig. 1

Fig. 2

Fig. 3

FIG. 1 is a top plan view of a hose guide for preventing damage to flower beds and the like embodying my new design.

FIG. 2 is an elevational view, and

FIG. 3 is a cross-sectional view, taken on the line 3—3 of FIG. 1.

The ground stake or shaft is broken away for convenience of illustration.

The characteristic feature of my design resides in the configuration of the pulley groove which in cross section is a deep near-parabolic curve with an apex where the pulley halves are joined, in combination with a thin peripheral edge, all as shown.

I claim:

The ornamental design for a hose guide for preventing damage to flower beds and the like, substantially as shown and described.
